UNITED STATES PATENT OFFICE.

JOHN G. MAGIN, OF ROCHESTER, NEW YORK, ASSIGNEE TO HENRY CONOLLY COMPANY,
OF ROCHESTER, NEW YORK, A CORPORATION OF NEW YORK.

LOOSE-LEAF BINDEE.

1,151,024.

Specification of Letters Patent. Patented Aug. 24, 1915.

Application filed July 17, 1913. Serial No. 779,574.

To all whom it may concern:

Be it known that I, JOHN G. MAGIN, of Rochester, in the county of Monroe and State of New York, have invented a new and useful Improvement in Loose-Leaf Binders, which improvement is fully set forth in the following specification and shewn in the accompanying drawings.

The present invention relates to loose-leaf binders and more particularly to that type in which the binder is provided with the removable transfer member which holds or positions the leaves in such a manner that the perforations in said leaves are alined in order that they may be quickly introduced over an impaling projection or projections of the binder, an object of the invention being to provide for transferring the leaves quickly from the impaling projection to the transfer member.

To these and other ends the invention consists in certain parts and combinations of parts all of which will be hereinafter described, the novel features being pointed out in the appended claims.

In the drawings: Figure 1 is a perspective view of a loose-leaf binder embodying the present improvements, the binder being opened for the purpose of transferring the leaves from the impaling projections to the transfer member; Fig. 2 is a detail view of the auxiliary transfer device which forms one of the important features of the present invention; Fig. 3 is a sectional view through the binder when the latter is in closed position and the auxiliary transfer devices are removed; Fig. 4 is a sectional view through the binder while the latter is open as in Fig. 1; Fig. 5 is a top view of one of the binder members or elements removed, showing the transfer member connected thereto; and Fig. 6 is a sectional view on the line *a—a*, Fig. 5.

The invention is herein shown as embodied in a binder of the type in which two cover members 1 and 2 are hinged at 3 to suitable connecting members or binding devices which, in turn, are hinged at 4 to a back piece 5. One of these connecting members or binding devices may be in the form of a bar 6 which carries the impaling means preferably comprising two posts 7 of elliptical cross section. The other connecting member or binding device may be in the form of a casing or box-like structure 8

carrying a locking or retaining means preferably in the form of a slide bar 9 pressed in one direction by a spring 10 to cause shoulders 11 thereon to cooperate with shoulders 12 on the impaling projections 7 60 after the latter have been introduced through openings 13 in the casing. The locking or retaining means is operated through a finger piece 14 on the locking bar 9.

Associated with the parts above described is a transfer member which preferably embodies a bar 15 having one or more laterally extending transfer projections 16 for entering openings in the leaves 17 while said leaves are supported on the impaling posts 7.

The foregoing type of binder is old and well known.

In two applications for Letters Patents filed by me on October 30th, 1912, the serial numbers of which are 728,656 and 728,657, I have shown and claimed structures in which means is provided for supporting the transfer member with its projections upright in proximity to the hinge of that cover which is secured to the connecting member on which the retaining means is arranged, these constructions being provided so that the leaves on the transfer member will have one of the cover members as a support when the transfer member is removed from the impaling means. In the present invention, another means for supporting the transfer member is provided for the purpose of securing the same results and in addition 80 thereto of permitting the transfer member to be held by the retaining means without providing any projections on the transfer member which would interfere with the resting of the transfer member upon a flat support. In this embodiment, instead of providing the projections on the transfer member for interlocking with the retaining means or similar locking means, projections 18 are 85 provided on the retaining or locking means, and are in the form of short posts carried by the bar 9 and extending through openings 19 in the casing 8, said posts being provided with shoulders 20 adapted to engage with the bar 15 after being passed through openings 21 in said bar. When the projections are provided on the retaining or locking means, it is desirable to provide a holding device for preventing the movement of the transfer bar 15 in its plane, and, to this end,

the transfer bar is interlocked with the connecting member or casing 8, this preferably being effected by the provision of a post 22 extending from the casing or connecting member 8 and adapted to be passed through an opening 23 in the transfer bar 15. With this arrangement, the transfer member may be quickly attached to and detached from the connecting member with the detaining means 16 for coöperating with the upper end of the impaling projections. The face of the transfer member, opposite that from which the transfer projections extend, is smooth and will permit the transfer member to rest upon a flat surface and, in addition thereto, to be connected to the retaining means so as to be held by the latter.

While the leaves may be taken singly from the impaling projections and deposited upon the projections of the transfer member, this requires a great deal of time as each leaf must be so positioned that the projections of the transfer member will pass through its openings. Therefore, a further feature of this invention is to obviate this difficulty and to this end one or more auxiliary transfer devices are provided which guide the leaves from the impaling projections 7 to the transfer projections 16. In this instance, two of such auxiliary transfer devices are provided each coöperating with one of the impaling projections and extending to the transfer member so that leaves from the impaling projections can be carried to the transfer member. These auxiliary transfer devices may be in the form of goose necks or U-shaped pieces 24 each having one arm 25 longer than the other arm 26. The arm 26 may interlock with the impaling post and, with this in view, the upper ends of said posts are provided with pockets 27 receiving projections 28 on the auxiliary transfer members. It will be noted that the impaling posts are larger in cross section than the auxiliary transfer devices so that the leaves pass freely on and over the auxiliary transfer device. The longer arms of the auxiliary devices are locked or held against swinging, preferably by being passed through openings 29 in the transfer bar 15 and the openings 13 in the casing 8, through which the impaling projections 7 are passed to be engaged by the locking bar 9. The latter also serves to hold the longer arms of the auxiliary transfer devices and, to this end, said arms are notched at 31 to provide shoulders for engagement by the locking bar.

Assume the parts are in the positions shown in Fig. 3 wherein the transfer member projects through certain openings in the leaves while the latter are held to the impaling projections 7 by means of the retaining bar 9. When it is desired to use the binder with a book typewriting machine or for any purpose wherein it is desirable to open the

book so that the leaves may be thrown or transferred from one cover to the other, the retaining member 9 is moved to free the connecting member 8 from the impaling posts 7 and the two covers with the back opened to a flattened condition as shown in Fig. 1. The transfer member is then connected to the retaining member so that its transfer projection 16 is upright. The auxiliary transfer members 24 are then fitted to the posts 7 and secured by the retaining member 9. The leaves may now be passed from the impaling posts 7 over the auxiliary transfer members 24 and on the transfer projections 16. In passing from the posts 7, the large openings in the sheets 17 permit the latter to pass freely on and over the auxiliary and transfer members 24. When it is desired to close the book, the locking member 9 is operated to free the auxiliary members which can then be detached from the impaling posts 7, after which the leaves on the transfer member 15 may be deposited bodily on the impaling projections 7 and the binder member or connecting member 8 interlocked with the impaling projections.

What I claim as my invention and desire to secure by Letters Patent is:

1. In a loose-leaf binder, the combination with a pair of binding members, one of which is provided with impaling means, of a transfer member having a transfer projection, and locking means carried by the other binder member and having means for engaging the impaling means, and also having a projection for engaging the transfer member.

2. In a loose-leaf binder, the combination with a pair of binder members, one of which is provided with impaling means, of a transfer member having a transfer projection, and a locking member carried by the other binder member and having a portion to engage the impaling means and also having a projection to engage the transfer member.

3. In a loose-leaf binder, the combination with a pair of binder members, one of which is provided with impaling means, of a transfer member embodying a bar having a laterally-extending transfer projection, and a locking member carried by the other binder member, adapted to engage the impaling means and provided with a projection for engagement with the transfer member.

4. In a loose-leaf binder, the combination with a binder member provided with a plurality of laterally-extending impaling projections, and a transfer member comprising a bar and a laterally-extending transfer projection, of a second binder member embodying a casing having openings for receiving the impaling projections, and a locking member mounted in said casing to engage the impaling projections, said locking member having a projection extending through the

casing to engage with the bar of the transfer member.

5. In a loose-leaf binder, the combination with a pair of binding members, one of which is provided with impaling means, of a transfer member having a transfer projection, locking means carried by the other binding member and adapted to engage the impaling means, a positioning projection arranged on the last mentioned binder member and adapted to engage the transfer member, and projections on the locking means adapted to engage the transfer member.

6. In a loose-leaf binder, the combination with the back piece, binder members hinged to the back piece and cover members hinged to the binder members, one of said binder members being in the form of a casing provided with openings, of a plurality of impaling projections extending laterally from the other one of the binding members, a transfer member embodying a bar and a transfer projection for cooperating with leaves on the impaling projections, a positioning projection extending from the first mentioned binder member to engage the bar of the transfer member, a locking bar arranged in the first mentioned binder member and adapted to engage the impaling projections when the latter are passed through the openings of said binding member, and a locking projection extending from the locking bar to the exterior of the binding member and adapted to engage the bar of the transfer member.

7. In a loose leaf binder, the combination with a backing member, a pair of binder members hinged to the backing member, one of said binder members being in the form of a casing having openings therein, and a pair of cover members connected to the binder members, of impaling and centering projections carried by the other binder member and holding the leaves in proper relation to each other, the free ends of said projections being arranged to enter openings in the casing binder member, locking means arranged in the casing binder member to engage the ends of the impaling and centering projections, and a transfer member adapted to be held by the locking means when the covers are arranged in a single plane and constructed to carry the sheets from the impaling projections to the cover by which the locking means is carried without removing the leaves from the binder.

8. In a loose leaf binder, the combination with a backing member, a pair of binder members hinged to the backing member, one of said binder members being in the form of a casing having openings therein, and a pair of cover members connected to the binder members, of impaling and centering projections carried by the other binder member and being adapted to pass through the

openings at their ends, locking means in the casing binder member for engaging said ends of the impaling projections, and goose necks adapted, when the two cover members lie in one plane, to interlock with the ends of the impaling projections and to pass through the openings in the casing to be engaged by the locking means.

9. In a loose-leaf binder, the combination with two cover members, a binder member supported by one cover member and having an impaling projection for passing through an opening in each of the leaves, of a transfer member supported by the other cover member and having a projection for passing through another opening in such leaves, and an auxiliary removable transfer device extending from the binder member to the transfer member to cause the leaves to be guided from the impaling projection to the transfer projection.

10. In a loose-leaf binder, the combination with two cover members having a binder member supported by one cover member and having a plurality of impaling projections, of a transfer member supported by the other cover member and embodying a bar having at least one transfer projection and removable auxiliary transfer devices each having a portion cooperating with one of the impaling projections and a portion cooperating with the bar of the transfer members.

11. In a loose-leaf binder, the combination with two cover members, a binder member supported by one cover member and having impaling projections formed with pockets in their free ends and a transfer member supported by the other cover member and embodying a bar and a transfer projection, said bar being provided with openings, of removable transfer devices having portions projecting into the pockets of the impaling projections and portions projecting into the openings of the transfer bar.

12. In a loose-leaf binder, the combination with two cover members, a binder member supported by one cover member and having a plurality of impaling projections and a transfer member supported by the other cover member and having at least one transfer projection, of removable auxiliary transfer devices each having a cross section smaller than the cross section of one of the impaling projections and each also having one end connected to one of the impaling projections and the other end connected to the transfer member to one side of the transfer projection.

13. In a loose-leaf binder, the combination with two cover members, a binder member supported by one cover member and having a plurality of impaling projections, and a transfer member supported by the other cover member and embodying a bar having openings and at least one transfer projec-

13. In a loose-leaf binder, the combination of auxiliary removable transfer devices each having a goose-neck-shape with one arm of each interlocked with one of the impaling projections, and the other arm fitted in one of the openings of the transfer bar.

14. In a loose-leaf binder, the combination with a back piece, of binder members hinged to the back piece, and cover members hinged to the binder members, of impaling means carried by one of the binder members, locking means carried by the other binder member for engaging the impaling means, a transfer member having a projection for cooperation with sheets on the impaling means, means for supporting said transfer member with its projection upright and in proximity to the hinge of that cover which is connected to the binder member having the locking means, and a removable auxiliary transfer device for directing leaves from the impaling means to the transfer projection while the transfer member is supported with its projection upright.

15. In a loose leaf binder, the combination with a back piece, binder members hinged to the back piece, and cover members hinged to the binder members, of impaling projections carried by one of the binder members, locking means carried by the other binder member for engaging the impaling projections, a transfer member having a transfer projection, said transfer member being adapted to be engaged by the locking means to be held by the latter with the projection

upright, and an auxiliary transfer device for directing the leaves from the impaling means to the transfer projections.

16. In a loose-leaf binder, the combination with a pair of binder members one of which is provided with impaling means, of a transfer member having a transfer projection, locking means carried by the other binder member and adapted to engage both the transfer member and the impaling means, and an auxiliary transfer device adapted to interlock with the impaling means and to be engaged by the locking means.

17. In a loose-leaf binder, the combination with a pair of binder members, one of which is provided with impaling projections and the other of which is in the form of a casing having openings therein to receive the impaling projections, of locking means for cooperating with those portions of the impaling projections passed through the openings, a transfer member having a transfer projection and adapted to be engaged by the locking means so as to be supported with its projection upright, and auxiliary transfer devices in the form of goose-necks having ends adapted to be interlocked with the impaling projections and ends adapted to be passed through the openings in the casing to be engaged by the locking means.
